UNITED STATES PATENT OFFICE.

GEORGE McD. JOHNS, OF ST. LOUIS, MISSOURI, ASSIGNOR TO W. N. MATTHEWS AND BROTHER, INC., OF ST. LOUIS, MISSOURI, A CORPORATION OF NEW MEXICO.

ATOMIZER.

1,355,339.

Specification of Letters Patent. Patented Oct. 12, 1920.

Application filed July 28, 1919. Serial No. 313,866.

To all whom it may concern:

Be it known that I, GEORGE McD. JOHNS, a citizen of the United States, residing at the city of St. Louis, State of Missouri, have 5 invented a certain new and useful Improvement in Atomizers, of which the following is a full, clear, and exact description, such as will enable others skilled in the art to which it appertains to make and use the 10 same, reference being had to the accompanying drawings, forming part of this specification, in which—

Figure 1 is a side elevational view of my atomizer.

15 Fig. 2 is a similar view partly in vertical section.

Fig. 3 is a similar view partly in vertical section, and,

20 Fig. 4 is a cross-sectional view showing the valve operating mechanism.

This invention relates to a new and useful improvement in atomizers for use in connection with paints, sprays and deodorizers, and the object is to operate the valves 25 which control the air and material by a valve mechanism which is entirely disconnected from the valves. In this manner I am enabled to use valves which require no packing joints except at the margins of the 30 diaphragms which operate the valves.

In the drawings, 1 indicates the barrel of the atomizer which at its forward end is provided with a nipple 2, the orifice of which is in communication with an opening 35 3 passing through the barrel. There is a nozzle 4 adjustably arranged on the forward end of the barrel whose chamber communicates with an opening 5 also passing through the barrel. These openings 3 and 5 40 diverge or pass to opposite sides of the barrel and communicate with chambers 6 and 7, respectively, on opposite sides of the main or body portion of the barrel which has a medial chamber 8 in which is located a 45 manually operable plunger 9 held outwardly by a spring 10. This plunger carries a cone 11 which operates between buttons 12 carried by diaphragms 13, said diaphragms being held in position by a skeleton ring 14 50 which carries packing glands 15 for the purpose of making a tight joint with the body portion of the barrel 1.

55 16 indicates a packing gland bearing against the outer side of skeleton ring 14, being interposed between said ring and a

connection 17 which connection is in the form of a chamber and carries a seat 18 for a valve stem 19, which valve stem carries a valve 20 bearing upon a valve seat formed on the outer face of the skeleton ring 14, 60 the valve stem 19 extending inwardly beyond the valve and being in registration with the stem of the button 12 carried by the diaphragm 13.

There is a coupling member 21 threaded 65 on the body portion of the barrel 1, which, when screwed down, holds the connecting member 17 tightly in any position in which it may be adjustably rotated. The spring 22 tends to hold the valve 20 to its seat. 70

A coupling provided with a valve 23 connects, by means of a flexible hose 24, with the material or air supply, as the case may be, and thus the ingress of these may be regulated. 75

The rear portion of the barrel terminates in a handle 1^a for convenience of manipulation in order that the spray may be directed to the desired point, this handle being held by the operator and the button on the stem being manipulated to coincidentally operate the diaphragms and the valves 20 to allow the air and material to pass through the openings 3 or 5 in the barrel, as the case may be, where the air will siphon (or blow) the 80 material out in the form of a spray. 85

While I have shown a cone as constituting the valve operating mechanism, it will, of course, be understood that a wedge will serve equally well; also, it will be seen that 90 the springs bearing on each oppositely disposed valve stem will balance the cone or wedge in its movement so that its operating rod or stem may pass freely through the handle. The valves are seated by the pressure of spiral springs within the diaphragm inclosed chambers, and hence their operating rods require no packing. 95

What I claim is:

1. An atomizer of the character described 100 comprising two adjustable members arranged on each side of a body portion, diaphragms carrying valves which control the passage of air and material through chambers formed by said members, and valve operating means arranged between said members. 105

2. An atomizer comprising a barrel portion, a handle portion in line with the barrel portion, valves for controlling the ingress of 110

air and material through chambers on each side of the barrel portion, there being a centrally arranged chamber in the barrel portion, and valve operating means located 5 within said last mentioned chamber.

3. An atomizer comprising a barrel portion, a handle portion, provided with a chamber, valve operating means arranged within said chamber, diaphragms on each 10 side of said chamber, and valves which are designed to be operated by said valve operating means.

4. An atomizer comprising a barrel portion and a handle, chambers on each side of 15 the barrel portion and rotatably adjustable

members forming the outer walls of said chambers in combination with means for holding said members in position.

5. An atomizer comprising a barrel portion and a handle, said barrel portion having 20 chambers on each side thereof, ingress tubes communicating with said chambers, diaphragms on the inner walls of said chambers and valve operating mechanism arranged between said diaphragms for operating 25 valves.

In testimony whereof I hereunto affix my signature this 21st day of July, 1919.

GEORGE McD. JOHNS.
